Filed May 8, 1923

Inventor:

William D. Haviland

By his Attorney,

Charles C. Gill.

UNITED STATES PATENT OFFICE.

WILLIAM D. HAVILAND, OF LIMOGES, FRANCE, ASSIGNOR TO THEODORE HAVILAND & CO., INCORPORATED, OF NEW YORK, N. Y., A CORPORATION OF NEW YORK.

DESIGN FOR A DISH, BOWL, OR SIMILAR ARTICLE.

Application filed May 8, 1923. Serial No. 6,107. Term of patent 14 years.

To all whom it may concern:

Be it known that I, WILLIAM D. HAVILAND, a citizen of the United States of America, and a resident of Limoges, France, have invented a new, original, and ornamental Design for a Dish, Bowl, or Similar Article, of which the following is a specification, reference being had to the accompanying drawings, forming a part thereof, and in which:—

Fig. 1 is a side elevation, and

Fig. 2 a top plan view of a dish, bowl embodying my design.

I claim:

The ornamental design for a dish, bowl, or similar article, as shown.

WILLIAM D. HAVILAND.
